UNITED STATES PATENT OFFICE.

MORGAN T. MORGAN, OF ANACONDA, MONTANA.

DESIGN FOR A DISTRIBUTER FOR APPLYING LINIMENT.

SPECIFICATION forming part of Design No. 29,731, dated November 29, 1898.

Application filed October 27, 1898. Serial No. 694,748. Term of patent 7 years.

To all whom it may concern:

Be it known that I, MORGAN T. MORGAN, a citizen of the United States, residing at Anaconda, in the county of Deer Lodge and State of Montana, have invented and produced a certain new and original Design for a Distributer for Applying Liniment; and I do declare the following to be a full, clear, and exact description of the invention, such as will enable others skilled in the art to which it appertains to make and use the same.

My invention relates to a new and original design for a distributer for applying liniment; and it consists of a distributer of the shape and configuration shown in the accompanying drawings, in which—

Figure 1 is a side view of the distributer, and Fig. 2 is a plan view.

The leading features of the distributer comprise a handle oval in cross-section and curved longitudinally and having a reduced end and a semispherical pad projecting from the reduced end. 20

What I claim is—

The design for a distributer for applying liniment, as herein shown and described. 25

In testimony whereof I have hereunto set my hand in presence of two subscribing witnesses.

MORGAN T. MORGAN.
